ALFRED E. PETERSEN, OF RIDGEFIELD PARK, NEW JERSEY, ASSIGNOR TO DEXTER FOLDER COMPANY, OF NEW YORK, N. Y., A CORPORATION OF NEW YORK

SHEET-FEEDING MECHANISM

Application filed January 7, 1927. Serial No. 159,684.

This invention relates to sheet feeding mechanism, and more particularly to the means employed for separating sheets from a pile which is automatically elevated as the sheets are separated therefrom and forwarded to the press or other instrumentality to be fed.

It has heretofore been customary to separate sheets of a pile carried on an automatically operated elevator by a rotary platen for producing a preliminary separation of a portion of the sheets at the top of the pile, a combing wheel cooperating with the platen to straighten the uppermost sheet across the flexure of the portion of sheets that have been partially separated by the rotary platen, and a reciprocating suction device consisting of two relatively movable sections one of which engages the straightened sheet and telescopes within the other section which is lifted with the telescoped section to separate the straightened sheet from the pile. It has been found, however, that when attempting to separate sheets of heavy stock such as twelve point or grades thicker than the same, the sheets of said heavy stock cannot be straightened by the combing wheel because of the relatively increased thickness of the sheet and its consequent increased resistance to the straightening action of said wheel, and that there is a tendency for the uppermost sheet and the one immediately below it to adhere so that two or more sheets are often separated at the same time by the suction device and simultaneously forwarded to the press, thus causing a jamming of the sheets in the latter, or when caliper mechanism is employed, increasing the work thereof and causing the press to be frequently stopped with the resulting loss of time to the printer and decreased production of the press.

The principal objects of this invention are to provide sheet separating mechanism which eliminates the disadvantages referred to; which will positively separate two sheets adhering in the manner stated; which causes the lowermost of two adhering sheets lifted by the suction device to drop back onto the pile and at the same time insures that the uppermost sheet will be retained in engage-

ment with the suction device and permanently separated thereby from the pile; which enables the combing wheel to be retained in an inoperative position while sheets of relatively great thickness are being separated; and which is a simply constructed, efficient and expeditious mechanism for separating and feeding single sheets of heavy grades of paper employed in the trade.

This invention will be more clearly understood by reference to the accompanying drawings which illustrate one mechanical embodiment of the inventive idea, and wherein—

Fig. 1 is a perspective view of the entire sheet separating mechanism;

Fig. 2 is a top plan view of said mechanism with certain parts broken away for purposes of clearer illustration;

Fig. 3 is a side elevation partly in section of the combing wheel, showing means for retaining the same in an inoperative position;

Fig. 4 is an enlarged vertical view of the suction device, showing means for separating two adhering sheets;

Fig. 5 is a diagrammatic side elevation of parts of the sheet separating mechanism, showing two adhering sheets picked up by the suction device;

Fig. 6 is a view similar to Fig. 5, showing the manner of separating the two adhering sheets; and

Fig. 7 is a view similar to Fig. 6, showing the sucker completely telescoped within its casing and the top sheet supported by said sucker and completely separated from the pile.

Referring to the drawings wherein like reference numerals designate like parts throughout the several views, 5 indicates a cross-bar adapted to be supported on the side frames of a pile feeder constructed in any suitable manner to automatically or otherwise elevate a pile of sheets 6 carried on the support 7 of said feeder (Fig. 1). Mounted on the cross-bar 5 for adjustment along the same transversely of the pile feeder, is a sheet separating mechanism, the component parts of which are generally duplicated adjacent both rear corners of the sheet pile so as to

provide two separate mechanisms which act to partially separate a portion of the uppermost sheets adjacent both said rear corners and straighten and separate the sheets successively from the pile before they are forwarded to the press or other instrumentalities to be fed. Since these separating mechanisms are substantially identical in their construction and operation, and since in some cases a single mechanism is employed, only one of the same is herein illustrated and described. This sheet separating mechanism preferably includes a bracket 8 slidably mounted on the cross bar 5 and in turn having slidably mounted thereon a separator frame 9 which may be adjusted vertically with respect to the sheet pile, as by a screw rod 10 and a hand wheel 11 fixed thereon.

Journaled in suitable bearings of the separator frame 9 is a shaft 12 having fixed on one end thereof a bevel gear 13 which meshes with a bevel gear 14 fixed on a stub shaft 15 journaled in a bearing bracket 16 that is mounted on the arm 17 of the separator frame (Fig. 2). The stub shaft 15 is connected, as by a universal joint 18, with a shaft 19 that is driven from the press or from any other suitable source of power. A gear casing 20 is freely mounted on the shaft 12 and has an arm 21 through which is threaded a thumb screw 22 that engages the frame 9 and serves to adjust the angular position of the gear casing 20 with respect to the shaft 12. This driven shaft 12 is provided with gear teeth 23 for driving a series of intermeshing gears 24, 25, 26 and 27 housed within the casing 20, the gear 27 being fixed on a stub shaft 28 to which is rigidly secured a rotary platen 29 that serves to partially separate a portion of the uppermost sheets of the pile and continuously support said portion and add sheets thereto as the pile is elevated and the sheets successively separated and forwarded to the press.

Arranged to cooperate with the rotary platen 29 is a combing wheel 30 which, when it is desired to separate sheets of relatively thin stock, such for example, as the various grades thinner than twelve point, serves to straighten the uppermost sheet before it is separated from the pile by the suction device hereinafter referred to. This combing wheel is secured on one end of a shaft 31 journaled in suitable bearings on an arm 32 loosely mounted on the shaft 12. The opposite end of the shaft 31 has fixed thereon a bevel gear 32' which meshes with a bevel gear 33 that is rigidly secured on the shaft 12. It will thus appear that the shaft, through the medium of gears 32 and 33, serves to drive the shaft 31 and the combing wheel 30. The combing wheel arm is automatically raised and lowered by a cam arm 34 (Fig. 3) pivotally mounted on a pin 35 carried on a lug 36 projecting from the separator frame 9. This

cam arm 34 is provided with a roller 37 which engages a cam 38 fixed on the shaft 12. Said cam arm is further provided with a plate 39 upon which rides a roller 40 journaled at 41 on an arm 42 that extends upwardly from the combing wheel arm 32.

In accordance with the present invention, means are provided for holding the combing wheel in an inoperative position away from the rotary platen and the sheet pile when the separator mechanism is being employed to separate relatively thick sheets such as twelve point or grades thicker than the same. Said means may be of any suitable construction, but as herein shown, the same preferably consists of a hook 43 that is secured at 44 to the arm 32. This hook 43, together with the arm 32 and combing wheel 30, is adapted to be manually lifted so that the hook may be engaged in an apertured lug 45 on the separator frame 9. Said lug and the hook 43 thus serve to support the combing wheel in the inoperative position with respect to the rotary platen and the sheet pile as shown in Fig. 3.

Carried on an upwardly extending arm 46 of the separator frame 9 is a pin 46' (Fig. 1) upon which is journaled a lever arm 47 to the free end of which is pivotally connected, as at 48, the upper end of a rod 49. The lower end of this rod 49 is provided with an angular slot 50 in which engages a stud 51 secured to the separator frame 9. When the rod 49 is raised and lowered by means to be presently described, the slot 50 and stud 51 serve to move said rod toward and away from the sheet pile so that like movements are imparted to a foot clamp 52 which is carried by the rod 49. This foot clamp 52 is formed at the lower end of a pipe 53 which is adjustably secured in a split collar 54 that is secured to the rod 49 by a bolt 55. A flexible tube 56 is connected with the upper end of the pipe 53 and serves to deliver air under pressure therethrough to the foot clamp from a pump or other suitable source (not shown). Pivotally connected, as at 57, with the arm 47 is a cam rod 58, the lower bifurcated end of which straddles the shaft 12 to center the cam rod with respect to said shaft. The cam rod 58 carries a pin 59 upon which is journaled a roller 60 which engages a cam 61 fixed on the shaft 12. Secured to the downwardly presented ends 62, 62 of the rod 58 is a plate 63 through a suitable opening in which extends a rod 64. This rod 64 has its upper end pivoted on a pin 65 and is provided with a collar 66 between which and the plate 63 is disposed a spring 67 which surrounds the rod 64 and tends to retain the cam rod 58 in its lowermost position. It will thus appear that, as the cam is rotated, the rod 49 will be raised and lowered, which movements are likewise imparted to the foot clamp 52 carried by said rod 49 and that through the described connections the foot clamp is caused

to periodically engage the top of the sheet pile.

Loosely mounted on the shaft 12 is a curved lever 67' which is raised and lowered by the 5 plate 39 through the medium of a roller 68 journaled at 69 on the curved lever 67' and engaging said plate 39. This curved lever has adjustably mounted thereon, as by a pin and slot connection 70, 71 and a split clamp 10 72, a suction pipe 73 the upper end of which is connected by a flexible tube 74 with a suitable source of suction (not shown). The lower end of said pipe 73 terminates in a plate 75 (Fig. 4) having a port 76 therein 15 communicating with the pipe 73 and with an arcuate-shaped casing 77 secured to the plate 75, as by set screws 78, 78. This casing 77 and the conduits connected therewith, form one part of a suction device that is raised and 20 lowered by the plate 39, and said suction device serves to separate the sheets successively from the pile 6. The other part of this suction device is comprised by an arcuate-shaped sucker 79 telescopically fitted in the 25 casing 77 so as to be projected from said casing when lowered therewith into engagement with the uppermost sheet of the pile and to be retracted within the casing 77 when the entire suction device is lifted to separate said 30 uppermost sheet from the pile. The telescoping sucker 79 is provided with a sheet gripper 80 and, when suction is applied within the device, the sucker 79 is telescoped within the casing 77 against the tension of coil 35 spring 81 (Fig. 5) surrounding an arcuate-shaped rod 82 which is pivoted at 83 to the sucker 79 and is slidably guided in an apertured lug 84 on the casing 77. The opposite ends of the spring 81 bear against a washer 40 81' and the lug 84 respectively, and said spring acts to distend the sucker 79 when the suction is broken in the pipe 73 and flexible tube 74.

In accordance with the present invention, 45 means are provided for preventing the suction device from permanently separating more than one sheet at a time from the pile when the sheets to be separated are of stock such, for example, as twelve point or grades 50 thicker than the same. The means last referred to is preferably constituted by a curved deflector finger 85 which is provided at its upper end with one or more slots 86, 86 and adapted to be detachably secured to 55 the casing 77 by screws 87, 87 which pass through the slots 86, 86 and are threaded into suitable openings in the casing 77. When sheets of relatively great thickness, such as those above referred to, are to be separated 60 by the mechanism described, the combing wheel is lifted to the inoperative position shown in Fig. 3 and retained in said position by engaging the hook 43 in the apertured lug 45. The deflector finger 85 is then secured to the casing by the means described,

so as to be positioned in the path of travel of the sheets lifted and separated from the pile by the sucker 79. The free end portion of the deflector 85 is curved as at 88, so that, if two or more sheets adhere and are simultaneously lifted from the pile by the sucker 79, as shown in Fig. 5, said adhering sheets will be bent by contact of the uppermost sheet with the deflector finger as the sucker 79 is telescoped within the casing 77. This bending of the sheets is clearly shown in Fig. 6, wherein the sucker 79 has been partially telescoped within the casing 77 and the uppermost sheet is being securely engaged with the gripper 80 by the suction in the separating device. Bending of the sheets, however, separates their adjacent edges and, as the sucker continues to recede within the casing, the curved free end portion 88 of the deflector finger engages the edge of the sheet immediately below the uppermost one so that the adhering sheets are separated and aerated therebetween, the uppermost sheet being retained in engagement with the gripper 80 and the additional sheet or sheets being deflected back onto the sheet pile and engaged by the foot clamp 52 as shown in Fig. 7. The curvature of the sheet deflector 85 is of a predetermined arc which insures that the uppermost sheet will not be detached from the sucker 79 by said deflector, but to further insure against such action, the deflector may be adjusted on the casing 77 by the screw and slot connections 86, 87, so that only the excess sheet or sheets will be detached from the sucker 79 as it telescopes within said casing.

What is claimed is:—

1. The combination with a device adapted to separate a sheet from a pile, of means movable at intervals toward and from the pile and past which said device travels, said means being adapted to deflect back onto the pile any sheet or sheets that may be separated therefrom with said first named sheet.
2. The combination with a device adapted to separate a sheet from a pile, of a curved automatically operated element movable at intervals toward and away from the pile and past which said device travels, said curved element being adapted to deflect back onto the pile any sheet or sheets that may be separated therefrom with said first named sheet.
3. The combination with a suction device having a reciprocating casing and a part 120 adapted to telescope therein and separate a sheet from a pile, of means on said casing spaced from the pile and past which said part travels, said means being adapted to deflect back onto the pile any sheet or sheets that may be separated therefrom with said first named sheet.
4. The combination with a suction device having an arcuate-shaped reciprocating casing and an arcuate-shaped sucker adapted to 130

- telescope within said casing and separate sheets from a pile, of a curved deflecting element carried by the arcuate-shaped casing for preventing said sucker from separating 5 more than one sheet at a time from said pile.
5. In a sheet separating mechanism the combination with a hollow casing, means for reciprocating the same, and a sucker member arranged to be projected from and telescoped 10 within said casing to separate a sheet from a pile, of means supported in spaced relation with the pile and past which said sucker member travels, said means being adapted to deflect back onto the pile any sheet or sheets 15 that may be separated therefrom with said first named sheet.
6. The combination with sheet separating mechanism comprising two parts one of which is alternately projected from and telescoped 20 within the other to separate a sheet from a pile, of means supported on the other of said parts in spaced relation with the pile and past which the first named part travels, said means being adapted to deflect back onto the pile any 25 sheet or sheets that may be separated therefrom with said first named sheet.
7. The combination with a sheet separating mechanism comprising a casing and a sucker member alternately projected from and telescoped 30 within the casing to separate a sheet from a pile, of means for preventing said sucker member from permanently separating more than one sheet at a time from the pile, said means comprising a curved deflector sup- 35 ported on the casing in spaced relation with the pile and adapted to bend adhering sheets on the traveling sucker member whereby said sheets are aerated and all but one of the same dropped back onto said pile.
- 40 8. In a sheet separating mechanism, the combination with a movable sucker member for separating a sheet from a pile, of an element mounted independently of the sucker member in spaced relation with the pile and 45 adapted when more than one sheet at a time is picked up by the sucker member and moved past said element, to bend the sheets relatively whereby they are aerated and the excess sheet or sheets dropped back onto the pile.
- 50 9. The combination with a device for separating a sheet from a pile, of a curved deflector mounted independently of said device in spaced relation with the pile, the curvature of said deflector being such that when 55 adhering sheets are moved past the same by the separating device said sheets are bent relatively by the deflector and all but one of them dropped back onto the pile.
- 60 10. The combination with a support for a pile of sheets and a device movable thereover for separating sheets successively from the top of the pile, of a deflector disposed over the pile in spaced relation therewith and mounted independently of the separating de- 65 vice to provide for movement of the same

past the deflector, said deflector being curved downwardly and outwardly to engage and bend adhering sheets on the separating device so that the uppermost sheet is retained in engagement with said device and the lowermost sheet or sheets are separated therefrom and drop back onto the pile. 70

11. The combination with a device for separating a sheet from a pile and a hollow foot clamp periodically engaging the pile, of a curved deflector supported in spaced relation with the pile and past which said device travels, the curvature of said deflector being such that when a plurality of sheets are picked up by the separating device and moved past the deflector, the latter relatively bends the adhering sheets whereby the sheet or sheets below the one engaged with the separating device may be aerated, dropped back onto the pile, and engaged by said foot clamp. 80

12. In a sheet separating mechanism, a rotary platen, a combing wheel, and a suction device, said elements being adapted to separate sheets of various grades thinner than one of a certain thickness, means for holding 90 the combing wheel in an inoperative position when said suction device is employed to separate sheets of various grades thicker than those first named, and means for preventing the suction device from separating more than 95 one at a time of said last-named sheets.

13. In a sheet separating mechanism, a rotary platen, a combing wheel, and a suction device, said elements being adapted to separate sheets of various grades thinner than one of a certain thickness, means for holding 100 the combing wheel in an inoperative position when said suction device is employed to separate sheets of various grades thicker than those first-named, and means adapted to be detachably secured on said suction device for preventing the same from separating more than one at a time of said last-named sheets. 105

In testimony whereof I have signed this specification.

ALFRED E. PETERSEN.
